DESIGN FOR A STRAIN TESTING INSTRUMENT

Arne J. Oker, Southbridge, Mass., assignor to
American Optical Company, Southbridge,
Mass., a voluntary association of Massachusetts

Application April 7, 1941, Serial No. 100,193

Term of patent 14 years

To all whom it may concern:

Be it known that I, Arne J. Oker, a citizen of the United States of America, residing at Southbridge, in the county of Worcester and State of Massachusetts, have invented a new, original, and ornamental Design for a Strain Testing Instrument, of which the following is a specification, reference being made to the accompanying drawing, forming a part thereof.

Fig. 1 is a perspective view of the strain testing instrument embodying my design.

Fig. 2 is a side view of the article shown in Fig. 1.

Fig. 3 is a front view of the article shown in Figs. 1 and 2.

I claim:

The ornamental design for a strain testing instrument, substantially as shown.

ARNE J. OKER.
